FURNACE CONSTRUCTION

Louis H. Hosbein, Glencoe, Ill., assignor to M. H. Detrick Company, Chicago, Ill., a corporation of Delaware

Application June 15, 1935, Serial No. 26,766
Renewed December 8, 1937

13 Claims. (Cl. 72—101)

This invention relates to the construction of furnace walls of the type wherein the heat-confining wall is formed of refractory blocks or tiles supported on an external metallic framework.

5 A general object of the invention is the provision of such a wall construction which is particularly well adapted to resist disintegration of the refractories by slagging, spalling and plastic deformation, and which practically eliminates 10 possibility of air or gas leakage through the joints between the refractories.

Another object is the provision of such a construction which admits of the use of refractory tiles of relatively small size, and provides for 5 the secure retention of the tiles against displacement from the wall, yet permits the assembling or erecting of the structure and the replacement of the tiles and the tile-supporting parts with facility.

10 Yet another object is the provision of such a construction which lends itself to both air cooling of the wall by circulation of air along the outer surfaces of the wall tiles and insulation of the wall by application of heat-insulating material at the outer surfaces of the tiles.

A more particular object of the invention is the provision of a wall construction having the above specified characteristics and wherein the juxtaposed tiles are intermeshed with one another in such fashion that the joints between the tiles are tortuous and the joints between the tiles in respective courses are staggered relative to those in subjacent and superjacent courses.

15 Another object is the provision of a construction having the above specified characteristics and in which the tiles are assembled in independently supported sections arranged one above another, with provision for accommodation of vertical expansion of one section relative to another, tiles of uniform size and shape being employed throughout the sections, excepting at the expansion joints and the wall terminals.

Other and further objects of the invention will 20 be pointed out or indicated hereinafter; or will be apparent to one skilled in the art upon an understanding of the invention or its employment in use.

In the accompanying drawings, forming a part 25 of this specification, I show certain wall constructions which embody the invention, but it is to be understood that these, and the following description of them, are presented merely by way of illustration, and that they are not to be construed in any fashion for the purpose of limiting

the appended claims short of the true and most comprehensive scope of the invention in the art.

In the drawings:

Fig. 1 is a perspective view of a portion of furnace wall structure embodying the invention in 5 one form;

Fig. 2 is a vertical sectional detail illustrating in side elevation one of the tile brackets employed in the construction shown in Fig. 1, and showing the relationship of some of the wall tiles 10 thereto;

Fig. 3 is a perspective view of a form of tile which may be employed in a wall structure embodying the invention;

Fig. 4 is a similar perspective view of the same 15 tile, showing the sides which are opposite to those shown in Fig. 3; and

Fig. 5 is a perspective view of a portion of another form of furnace wall structure embodying the invention.

20 The nature of the invention can be most quickly ascertained from a consideration of the constructions shown in the drawings, which will now be described.

25 Referring first to the construction illustrated in Figs. 1 and 2, it is to be understood that the reference numeral 10 designates columns or upright members, preferably made of structural steel, which form the principal load-carrying members of the external metallic frame which 30 carries the refractory wall. There is a number of these upright frame members ranged along the sides of the furnace and suitably supported in upright position and connected by such transverse frame members as may be necessary to 35 form a self-sustaining frame structure. Transverse members 11 are connected to and supported by the upright members 10 at intervals one above another. These transverse members preferably are formed of a metal which is well 40 qualified to retain its strength and stiffness at elevated temperatures, e. g., cast iron. They are secured to the upright members 10 by bolts 12 which pass through spacing members 14. As seen in Fig. 2, the transverse member 11 has a top ledge 11a from which rises a top flange 11b, and at its bottom has an inwardly projecting flange 11c.

The wall tiles 15 are of the form illustrated in 45 Figs. 3 and 4, being of generally rectangular 50 form and of relatively small cross-sectional size, e. g., three inches by six inches. Their broader side faces are each provided with a series of projections 15a interspaced by seats 15b, a series of projections 15c interspaced by seats 15d, and a 55

series of short projections $15e$ interspaced by seats $15f$, the projections on one side being opposite corresponding seats on the opposite side. Their narrower side faces are provided with a series of projections $15g$ interspaced by seats $15h$, the projections on one of said faces being opposite the seats on the other.

At a suitable distance from their outer ends, the narrower side faces are grooved across as shown at M and N, to form shoulders $15j$ and $15k$, said shoulders being of approximately the same width, but the groove N being substantially deeper than the groove M, so that the shoulder $15k$ is inset from its side of the tile, whereas the shoulder $15j$ is approximately flush with its side of the tile.

For supporting the tiles on the transverse members 11 , I provide a plurality of tile supports or brackets 16 of suitable heat-resistant metal, such as cast iron. The bracket 16 has a hook portion adapted to hook over the flange $11b$ and rest upon the ledge $11a$, a lug $16b$ adapted to engage under the flange $11c$, and a shoulder $16c$ adapted to abut the inner margin of the flange $11c$. By this means the bracket is adapted to be supported in vertical position on the transverse member 11 . At each side the bracket has a laterally projecting shelf $16d$ spaced at a distance from its lower end, and at its lower end it has laterally projecting lugs $16e$. Above the shelf $16d$ the bracket has at its inner margin laterally projecting inner lugs $16f$, and, toward its outer margin, laterally projecting outer lugs $16g$. The horizontal distance between the inner lugs $16f$ and the outer lugs $16g$ is but slightly greater than the width of the tile shoulders $15j$ and $15k$. The spacing of the lugs $16e$ from the shelf $16d$ is somewhat greater than the width of the narrower side faces of the tile.

In the construction illustrated in Fig. 1, the center-to-center horizontal spacing of the brackets 16 is approximately equal to the width of two of the tiles 15 , and I provide the base tiles 17 which are of sufficient width to bridge the space between adjacent brackets. These tiles have shoulders corresponding to the shoulders $15j$ of the tiles 15 , but said tiles 17 are considerably shorter than the tiles 15 . The tiles 17 are slid down on the brackets until their shoulders rest on the shelves $16d$, said shoulders engaging between the lowermost inner lugs $16f$ and outer lugs $16g$. Thereby the tiles 17 are supported on the brackets and held against tilting. Thus a row of the base tiles 17 is supported at the bottom of each wall section.

The lowermost course of tiles 15 for the wall section is then placed on the base tiles 17 . Two tiles 15 are disposed between each two adjacent brackets, their shoulders $15j$ being toward the same side and the projections $15g$ and seats $15h$ of the juxtaposed tiles being intermeshed. The tiles 15 are slid down on the brackets 16 so that the shoulder $15j$ of one of said tiles engages between the lugs $16f$ and $16g$ of one of the brackets, and the shoulder $15k$ of the other of said tiles engages between said lugs of the adjacent bracket. The tiles 15 of the lower course are thus supported with portions projecting inwardly beyond the base tiles 17 .

The tiles which form the second course of the section are then similarly engaged with the brackets 16 , but the tiles of this course are reversed or inverted with respect to the tiles of the lowermost course, in the sense that their shoulders $15k$ are disposed over the shoulders $15j$ of said lower

tiles. Consequently, the joints between the tiles of the second course will be staggered or offset relative to the joints between the tiles of the lowermost course, and the projections $15a$, $15c$ and $15e$, and seats $15b$, $15d$ and $15f$ of the tiles in one course will intermesh with those of tiles in the other course.

The wall section is then further built up by addition of further courses of tiles 15 , the tiles in each course being reversed in position relative to those of the next lower course, in the sense above explained. Consequently, each tile in the wall section, with the exception of the terminal tiles at the top, bottom and sides of each section, will be intermeshed with two tiles in the subjacent course and two in the superjacent course, as well as with the two juxtaposed tiles in its own course. This provides a refractory wall in which all of the joints are tortuous and the vertically running joints are staggered.

It will be understood from the foregoing that each horizontal row of brackets supports a wall section made up of a plurality of superimposed courses of tiles, and that each section is supported on the metallic framework independently of the sections above and below it. It will be noted also that some of the tiles in a section have anchorage connection, by means of the lugs $16f$, with the brackets which support them. Other tiles of such section have anchorage connection with the brackets which support the next superjacent section, e. g., the tiles in the course designated by the reference character R in Fig. 1 have anchorage connection with the brackets in the upper row, by engagement of their shoulders with the lower lugs $16e$ of said brackets. Tiles in some of the courses do not have anchorage connection directly with any of the brackets, but are retained against displacement from the wall by their intermeshing engagement with other tiles. In the construction shown in Fig. 1, such tiles are those in the courses designated S and T.

At the top of each section is provided an expansion joint construction which accommodates its expansion upwardly relative to the superjacent section. A layer of compressible refractory material 18 is provided between the topmost course of tiles 15 and the superjacent base tiles 17 , to seal the intervening space. On the portions of the topmost tiles 15 , which project inwardly beyond the base tiles 17 , is laid a course of short tiles 19 . These have their faces formed with seats and projections corresponding with those of the tiles 15 , so that they intermesh with one another and with the tiles 15 upon which they rest, and are thereby held against dislodgment from the wall, their outer ends being in contact with the base tiles 17 . The upper faces of the tiles 19 are spaced below the tiles 15 of the superjacent section by a distance such as to permit the tiles 19 being lifted out of meshing engagement with the tiles upon which they rest, so as to permit said tiles 19 to be withdrawn inwardly from the wall. This space between the tiles 19 and the superjacent tiles 15 is filled with a layer of compressible refractory material 20 . The construction provides a tortuous expansion joint which forms an effective seal between the sections, yet permits expansion of the lower section upwardly relative to the superjacent section, and permits tiles in any section to be removed and replaced without disturbing tiles in any other section. The short tiles 19 may be of the same width as the tiles 15 , or they may be of double that width, as illustrated by the tile $19'$ in Fig. 1.

If it is desired to insulate the refractory wall, slabs 21 of insulating material may be arranged against the outer faces of the wall tiles, and the space between the wall tiles and the transverse members 11 may be filled with plastic insulating material as indicated at 22 in Fig. 1. The insulating material may be covered externally by sheet metal panels 24 removably secured to the upright members 10 by means of clamping cleats 25 bolted to the members 10. If it is desired to cool the refractory wall, the space between the panels 24 and the wall refractories may be left unobstructed, so that air may be circulated therein along the outer surfaces of the wall refractories and across the transverse members 11 and the portions of the brackets 16 which are exposed in that space.

Replacements of tiles in any section may be made by picking out the joint material 20 over the affected portion of the section, breaking out one of the tiles 19, removing the other tiles 19 by lifting them upwardly, then moving them laterally, and then withdrawing them inwardly, and then removing the subjacent tiles 15 individually by prying them upwardly and withdrawing them inwardly. New tiles may then be inserted in the affected locality as above described, the lateral projections 15g of the last tile 19 being chipped off so that it may be slid into place.

The construction illustrated in Fig. 5 is designed to afford greater space between the wall refractories and the supporting framework, so as to accommodate circulation of a greater volume of air. In this construction the transverse members 11 may be made of structural steel, the tile-supporting brackets 26 being designed to support the refractory wall at a greater distance from the transverse members. In this construction the bracket 26 has an upper arm 26a which hooks onto one of the transverse members 11, and a bottom arm 26b which at its outer end abuts against the next lower transverse member 11'. Each bracket has a shelf 26c which extends inwardly and laterally and which affords a support for the tiles 15 of the lowermost course of the wall section, the bracket also having laterally extending inner flanges 26d and outer flanges 26e between which the shoulders of the tiles are engaged, to hold the tiles against tilting, as in the manner above described with reference to the lugs 16f and 16g. A construction employing base tiles such as those designated 17 in Fig. 1 may also be employed with brackets of this type, in which event the shelves 16 may be terminated flush with the inner flanges 16d, instead of being extended inwardly therefrom. Such a construction would also have an expansion joint construction employing short tiles such as those designated 19 or 19' in Fig. 1. The expansion joint construction shown in Fig. 5 is provided by a layer of compressible refractory material 27 filling the space between the topmost tiles 15 of one section and the bottommost tiles 16 of the superjacent section. In the construction shown in Fig. 5 the brackets 26 in each row are arranged in staggered relationship to those in the subjacent and superjacent rows, and the tiles in one section do not have anchoring engagement with the brackets which support the superjacent section.

In the erecting of the refractory wall, the tiles preferably are dipped in or "buttered" with a thin slurry of fire clay, for the purpose of filling in voids between the surfaces of the intermeshing tiles. This contributes to the tightness of the

joints, and when the material is dried, it is retained against sifting out by the intermeshing projections and seats. It is to be understood that the intermeshing projections and seats of the tiles do not contact at all points, and that thereby slight adjustment of one tile relative to another may take place incident to expansion and contraction of the tiles upon heating and cooling, the fire clay jointing material being of friable character when dry such as to accommodate slight relative movements of the tiles.

It is further to be noted that when the tiles are assembled in the wall as above described, the short marginal projections 15e of the tiles in one course interlock with those of tiles in the next course, and that thereby the tiles in a course are retained against separating from each other to an extent such as to un-mesh their lateral projections 15g and seats 15h. In Fig. 1 such interlocking portions are indicated at I.

From the foregoing it will be apparent that the construction provides a refractory wall in which the tiles are very securely and closely intermeshed with one another throughout the greater portion of the wall's thickness, but that at the same time suitable accommodation is afforded for expansion and contraction of the tiles, such as to avoid the breaking off of their intermeshing portions. Several important advantages are thereby obtained. Fragments of the tiles which might be broken off by thermal strains are retained against falling out of the wall, and so continue to protect adjacent tile surfaces. All of the joints are tortuous, thereby minimizing possibility of leakage and also retaining the jointing material from working out and slag from working in between the tiles. Laterally juxtaposed tiles are retained against separating, so that even if an inner end portion of the tile should be fractured off by thermal strains, the fire and slag cannot work in behind it through a vertical joint. By virtue of the intermeshing of the tiles, they are held against displacement from the wall, even though not anchored directly to the frame members. Consequently, it is necessary to anchor only certain of the tiles to the framework in order to maintain the entire wall in proper vertical position. This permits a considerable reduction in the amount of metal, as represented by the brackets 16, which it is necessary to imbed or pocket between the tiles. Accordingly, the brackets are not subjected to deterioration by heat, and conduction of heat through the brackets to the transverse members and columns is minimized. The wall is easily assembled and easily repaired, and the refractory portion is made up almost entirely of tiles of the same size and form, said tiles being of relatively small cross-sectional dimension, so that each exposes but a small area at the inside of the wall.

What I claim is:

1. In a furnace wall structure, the combination of a supporting frame, vertically spaced rows of horizontally spaced tile supports carried on said frame, refractory wall sections supported independently on said tile supports one above another, said sections being made up of horizontally running courses of refractory tiles arranged in pairs spanning the spaces between juxtaposed tile supports, the tiles in respective courses being intermeshed with the juxtaposed tiles in the same course and with the juxtaposed tiles in the subjacent and superjacent courses in the section, whereby the joints between the tiles are tortuous transversely of the wall, some only of the tiles

- having anchoring engagement with the tile supports, and a compressible filler of refractory material between adjacent wall sections and intermeshed with the lowermost tiles of one and the uppermost tiles of the other to form expansion joints between the sections.
5. A furnace wall structure as specified in claim 1 and wherein the joints between tiles in respective courses are offset laterally relative to those between tiles in the superjacent and subjacent courses.
6. A furnace wall structure comprising an upright supporting frame, horizontally spaced tile supports carried on said frame, horizontally running courses of refractory tiles supported on said tile supports and arranged in pairs spanning the spaces between juxtaposed tile supports, said tiles having their lateral faces formed with projections and seats and their upper and lower faces formed with projections and seats, said tiles being disposed with projections and seats of their lateral faces intermeshing with seats and projections of juxtaposed tiles in the same course and with projections and seats of their upper and lower faces intermeshing with seats and projections of tiles in superjacent and subjacent courses, and some of said tiles having lateral anchoring engagement with the tile supports, whereby the tiles are held against displacement inwardly from the frame.
7. A furnace wall structure as specified in claim 3 and wherein the joints between tiles in respective courses are offset relative to joints between tiles in superjacent and subjacent courses.
8. A furnace wall structure as specified in claim 3 and wherein projections and seats of respective tiles are intermeshed with seats and projections of two tiles in a superjacent course and with seats and projections of two tiles in a subjacent course.
9. A furnace wall structure as specified in claim 3 and wherein tiles in each course have their projections and seats intermeshed with seats and projections of a plurality of tiles in respective subjacent and superjacent courses in a manner to hold the tiles in respective courses against lateral movement such as to un-mesh their lateral projections and seats.
10. In a furnace wall structure, the combination of a frame, tile supports carried on the frame and extending laterally therefrom in vertically spaced horizontal rows, wall sections supported on respective rows of tile supports, each of said wall sections being made up of a plurality of superimposed courses of refractory tiles, the tiles in respective courses having intermeshing engagement with the tiles in superjacent and subjacent courses whereby the tiles are held against inward displacement relative to one another, tiles in the lower courses of respective sections being anchored to their tile supports and tiles in an upper course of respective sections being anchored to tile supports which support the superjacent section.
11. In a furnace wall structure, the combination of a frame, wall sections supported independently on the frame one above another, respective wall sections being made up of a plurality of superimposed courses of refractory tiles, some of the tiles having anchorage connection with the frame to hold them against displacement inwardly, tiles in the topmost course in a section having intermeshing engagement with those in the subjacent course and having their upper surfaces spaced below the superjacent tiles of the next higher section a distance such as to permit their being lifted out of intermeshing engagement with their subjacent tiles, and a removable filler filling the space between the tiles of said topmost course and the tiles superjacent thereto.
12. In a furnace wall structure, an upright frame, vertically spaced rows of horizontally spaced tile supports carried thereon, refractory tiles arranged in horizontal courses disposed one upon another and supported on said tile supports, means on said tile supports engaging outer end portions of some of said tiles to hold them against displacement inwardly, inner portions of said tiles being provided on each of their upper, lower and lateral faces with a plurality of transversely extending projections and seats, and the projections and seats of juxtaposed tiles being in intermeshing relationship.
13. In a furnace wall, the combination of brackets having vertically extending web portions carrying laterally projecting inner and outer lugs adjacent opposite edges and laterally extending shelf portions below said lugs, and refractory tiles supported by said shelf portions but having their center of weight beyond the same, said tiles having lateral shoulders engaged between the inner and outer lugs of the brackets, the tiles thereby being held against tilting across the inner margins of the shelf portions.
14. In a furnace wall, a combination as specified in claim 10 and including tiles arranged one upon another and having shoulders engaged between the inner and outer lugs, the superimposed tiles being in intermeshing engagement by means of projections and seats formed on their contiguous sides.
15. In a furnace wall structure, an upright frame, vertically spaced rows of horizontally spaced tile supports carried on said frame, wall sections each comprising a plurality of horizontal courses of refractory tiles supported on said tile supports, said tiles having their upper and lower faces formed with projections and seats and the tiles being arranged with the projections and seats of tiles in abutting courses in intermeshing engagement, tile engaging elements on the tile supports, said tile engaging elements having anchoring engagement with tiles in some of the courses whereby the intermeshed tiles are held against displacement inwardly from the frame, said tile engaging elements being spaced apart from one another vertically to permit inward withdrawal of the tiles engaged therewith after such tiles are lifted vertically out of intermeshing engagement with the subjacent tiles.
16. In a furnace wall structure, an upper tile anchoring member for a single tile column, an independent lower tile support and anchoring member spaced from said upper anchoring member, an upper refractory tile engaging said upper tile anchoring member, a lower tile resting on and engaging said lower support and tile anchoring member, and a series of intermediate tiles interlocked with said upper and lower tiles and with each other.
